UNITED STATES PATENT OFFICE.

HENRY TANNER, OF CHICAGO, ILLINOIS.

FIRE-BRICK.

1,164,680.

Specification of Letters Patent. Patented Dec. 21, 1915.

Application filed November 21, 1912. Serial No. 732,662.

To all whom it may concern:

Be it known that I, HENRY TANNER, a citizen of the United States of America, residing at the city of Chicago, in the county of Cook and State of Illinois, have invented certain new and useful Improvements in Fire-Bricks, of which the following is a specification.

My invention relates to heating furnaces, and particularly to those having a flat ignition arch. These are generally used in connection with chain grates by which fuel is fed under steam boilers. A supporting framework is necessary to hold the fire brick in place, and the brick perform the double office of providing a closed flat roof or "arch" and of protecting the supporting framework from the otherwise destructive heat. Heretofore the brick have been supported by placing them in single or double rows between each two beams or supports, the latter being flanged to engage with grooves in the sides of the brick adjacent thereto. The joints between the bricks being thus alined with the supporting members form a point through which the heat readily penetrates to the support. This is especially true when the joints are not properly fitted or where, as is frequently the case, the intense heat causes an expansion and contraction which opens the joints between the brick. It has been sought to minimize this difficulty by providing the bricks with a horizontally placed tongue-and-grooved beading, but the protection is not complete.

By my invention the fire brick are centrally suspended on the supporting members completely surrounding the portions nearest the fire and protecting them from the disintegrating effects of the heat.

The principles of my invention are illustrated in the drawings, in which—

A in Figure 1 shows a perspective view of one of my improved tiles; B in Fig. 2 is a modified form thereof; Figs. 3 and 4 are partial sections taken respectively on the lines 3—3 and 4—4 of Figs. 1 and 2; Fig. 5 is a partial section on the line 5—5 of Fig. 6; Fig. 6 is a reduced representation of an arch support to illustrate the application of my improved brick thereto.

The brick shown in Fig. 1 has a transverse groove 1, which is undercut at 2, and adapted to receive the metallic arch support 4. The latter has a transverse flange 5 on

its lower edge, making it T-shaped in cross section to correspond to the form of the slot as shown.

A modified form of the brick is shown in Fig. 2. The slot 1' is not extended through the entire thickness of the brick, but the undercut portion 2' is extended beyond the front portion of the slot, so that the advanced portion 5' of the hanger flanges will seat within the pocket thus formed, fully protecting the advanced end of the hanger support.

It will be seen that by using one or the other of the forms shown, the arch supports may be completely protected, both as to the main body portion and as to an extended end or tip. The heat which may go between the bricks passes upward between the hangers without impinging upon them, thereby greatly increasing their life. The extreme end of the hangers is protected by being inclosed in a packet provided therefor, and even when this most exposed portion is destroyed protection is provided for the portion of the support in the rear thereof until proper repairs can be made.

I claim:

1. A furnace arch including a beam of inverted T-shape in cross-section, a plurality of fire bricks having centrally placed grooves in their upper edges extending from the front face to the back face thereof and entirely therethrough and supported on said beam, said grooves corresponding in cross-section to the cross-section of said beam, the lower flanges of the beam projecting beyond the web thereof, and end blocks having a centrally placed undercut groove, said groove being extended to form a pocket to receive the said extended ends of the beam.

2. The combination with a furnace arch beam having its lower edges transversely extended to form flanges parallel with the body thereof, said flanges being extended from the end of said beam, of a fire brick having a centrally placed undercut groove on its upper face adapted to take the flanges on said beams, the undercut portion being extended to form a pocket in the same horizontal plane, said groove and pocket being adapted to receive the said flanges and the extended portion thereof.

3. The combination with a furnace arch beam having a vertical web and a transverse flange on its lower edge to form an inverted T in cross section, the said transverse

flange having an advanced portion projected beyond the end of the vertical flange, of a fire brick having a centrally placed undercut groove, said groove being extended to form a pocket to receive the said advanced portion of the horizontal flange.

4. The combination with a furnace arch beam having a vertical web and a transverse flange on its lower edge to form an inverted T in cross section, the said transverse flange having an advanced portion projected beyond the end of the vertical flange, said arch beam being further provided with a removable tip having a vertical web and 10 a transverse flange on its lower side to form 15 an inverted T in cross section, the said trans-

verse flange having an advanced portion projected beyond the end of the vertical flange, of a plurality of fire bricks having centrally placed undercut grooves, said 20 grooves being extended to form pockets to receive the said advanced portions of the horizontal flanges.

In witness whereof, I have hereunto subscribed my name this 11th day of November 25 1912, in the presence of two subscribing witnesses.

HENRY TANNER.
